Primary Examiner — Barbara Fox*Assistant Examiner* — Mary Claire Ramirez(74) *Attorney, Agent, or Firm* — Ladas & Parry LLP(57) **CLAIM**

The ornamental design for an earphone, as shown and described.

DESCRIPTION

FIG. 1 is a front elevational view of an earphone showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left, top perspective view thereof;

FIG. 8 is a rear, right, bottom perspective view thereof;

FIG. 9 is a rear, right bottom perspective view of the earphone in a state of use; and,

FIG. 10 is front view thereof.

The broken lines in FIGS. 4, 6, 8 and at the bottom of FIG. 9 depict portions of the earphone that form no part of the claimed design. The other broken lines in FIG. 9 and the broken lines in FIG. 10 depict environment and form no part of the claimed design.

1 Claim, 10 Drawing Sheets(56)
